C. BRAMMING

ELECTRIC LAMP FOR RADIOS

Filed July 30, 1925

Fig. 1.

Inventor: Carl Bramming
By Gillson, Mann & Cox
Atteys

UNITED STATES PATENT OFFICE.

CARL BRAMMING, OF CHICAGO, ILLINOIS, ASSIGNOR TO ACCESSORIES MANUFACTURING COMPANY, A CORPORATION OF ILLINOIS.

ELECTRIC LAMP FOR RADIOS.

Application filed July 30, 1925. Serial No. 46,936.

The invention relates to lamps, and more particularly to electric lamps, for radio cabinets.

One of the objects of the invention is the provision of new and improved lamp support that is small enough to be conveniently supported on a radio cabinet and that has means whereby the electric energy supplied for lighting the lamp may be taken from the battery employed in the operation of the radio mechanism.

Another object of the invention is the provision of new and improved means for adjusting the lamp relative to its base, and to the radio cabinet on which it is supported.

A still further object of the invention is the provision of a new and improved lamp support that is provided with a cheap and efficient switch mechanism, bulb holder and the like.

Another object of the invention is the provision of new and improved lamp support that is cheap to manufacture, easily assembled, readily adjusted when in use, efficient and durable, and that is not likely to become broken or get out of order.

Other and further objects and advantages will appear from the following description taken in connection with the accompanying drawings, in which—

Fig. 1 is a perspective view of a radio cabinet showing my invention in position thereon;

Fig. 2 is an elevation of the lamp;

Fig. 3 is a view at right angles from that shown in Fig. 2, with parts in section;

Fig. 4 is a bottom plan view of the hood or shade;

Fig. 5 is a plan view of a portion of the switch mechanism; and

Fig. 6 is a top plan view of an insulating disk used in the construction of the switch.

The support for the electric lamp is especially adapted for supporting a small electric light bulb for illuminating the dial plates of a radio cabinet. The current for lighting the lamp may be, and preferably is, supplied from one of the batteries constituting the radio equipment. While the lamp is diminutive in size, and is especially designed for illuminating the dial plates of radio cabinets, it is understood that it is not limited in its use and size to this relation.

For convenience in illustration, however, the device is shown as being associated with a

radio device in which the reference numeral 10 designates a radio cabinet which may be of any approved construction. The cabinet is provided with one or more dial plates 11 and knobs 12 for adjusting the receiving mechanism, as is usual in such constructions. The conventional amplifying horn is shown at 13.

Since the specific construction of the radio mechanism constitutes no part of the present invention, it is not thought necessary to further illustrate or describe the same.

The readings of the dials of a radio equipment indicating the adjustments of the receiving mechanism for different stations having once been ascertained by experiment, the operator may at any time after that tune in on any of those stations while they are broadcasting, by resetting the dials as indicated on his chart or record. It

is therefore desirable that the dials of the radio cabinet be well illuminated so that the legends or markings thereon may be plainly visible in order to make the proper adjustments readily and easily. Radio apparatus

has come to be a valuable if not a necessary part of the equipment of tourists and others traveling about the country for pleasure, and it is very desirable that a lamp be provided that will be sufficient to illuminate the dials but which will be compact and adjustable and that may be operated from one of the batteries of the set. The principal object of the present invention is the provision of a lamp that is especially adapted for illuminating the dial plates of radio equipment.

In the form of the device selected to illustrate one embodiment of the invention, a hollow metallic base 14 is employed having a bifurcated extension 15 in which is pivotally mounted an arm 16 which may if desired be slightly curved as shown in Fig. 3. The upper end of the arm 16 is adapted to be pivoted between the brackets 17 and 18 rigidly secured to a hood or lamp shade 19 concave in cross-section. The pivot 21 at the upper end of the arm 16 is tapped into plate 18 and the pivot 22 at the lower end of the arm engages a threaded opening in one of the furcations 20 whereby these parts may be clamped to the arm to constitute a friction hinge for holding the arm and the hood or shade in adjusted position.

The base 14 is hollow and a switch mechanism is mounted therein. The hollow base

is provided with an annular ledge or shoulder 23 against which a circular disk 24 of insulating material is adapted to engage. The disk 24 is provided with an extension 5 25 which extends outwardly through a slot 26 in the base 14 and is adapted to be employed as a thumb piece for operating the switch. The disk 24 is provided with two contact members 27 and 28 which extend 10 through the said disk. A wire or conductor 29 is rigidly connected to one of the contact members, as 27, and extends upwardly through the hollow arm 16.

The base 14 is also provided with a ledge 15 or shoulder 31 against which a disk 32 of insulating material is secured. The disk 32 is secured in position by any suitable means, as the screws 33. The disk 32 is provided 20 with a pair of spring contact members 34 and 35 which are adapted to be engaged by the contact members 27 and 28 on the disk 24.

Suitable conductors 36 are rigidly connected to the contact members 34 and 35 and 25 are adapted to be connected to the binding posts of one of the batteries. The contact member 28 on the disk 24 is provided with an extension 37 for engaging the shoulder 23 for grounding said contact member.

Suitable means are provided for mounting 30 the electric light bulb within the hood or shade 19. As shown, a metallic bracket 38 is employed for this purpose. The bracket 38 is provided with a circular opening 39 for receiving the base 40 of the bulb 41. Slots 42 are provided for accommodating the retaining lugs 43. The bracket 44 is also provided with depending fingers 44 for engaging the sides of the base of the bulb for holding the same in position. The bracket 38 is provided with an angular bifurcated extension 45 which is adapted to 45 be attached to an insulating member 46 which is secured to the hood or shade 19. The extension 45, insulating member 46 and brackets 17 and 18 are preferably secured together by screws 47 that are tapped into the furcations of the extension 45.

The bracket 38 is provided with recesses 50 or sockets 48 for receiving the retaining lugs 43 of the base 40. The lugs 43 are held in the recesses 48 by a spring contact member 49 which engages the central contact member 51 of the base 40. The spring 55 contact member 49 is rigidly secured to the insulating member 46 as by means of eyelets between the furcations of the extension 45 and out of contact therewith. Preferably a strip of insulating material 50 is employed to prevent contact of the fastening means with the hood and short circuiting the lamp. The strip extends above the upper end of the spring 49 as shown in Fig. 3. It may be clamped in position between the insulating member 46 and the hood 19 by the

screws 47. The conductor 29 is connected to the spring contact member 49 as by means of the rivet 52 which holds the said contact member in position. In attaching the bulb 41 the same is turned so the lugs 43 will register with the slots 42 after which the same is forced upward against the spring 49 and turned until the lugs register with and engage the recesses 48.

The base 40 of the bulb is grounded on the 55 arm 16 through the bracket 38 and the screws 47. By means of this arrangement only one conductor 29 need be employed between the contact members 27 and 28 and the electric light bulb, the other terminals being 59 grounded on the supporting arm 16.

By means of the adjusting screws 21 and 22 the desired amount of friction may be applied to the joints so that the parts will be retained in any adjusted position to which they may be moved. By providing joints at 85 both ends of the supporting arm 16 the hood and bulb may be adjusted to the desired position to give the best results.

In tracing the current, the same may, for 90 convenience, be considered as entering through one of the conductor members 36, thence through the contact members 34 and 27 of the switch, then through the conductor 29, spring contact member 49 and through 95 the filament. On return it passes through the base 40, bracket or plate 38, arm 16, contact members 28 and 35 and back through the other conductor 36.

The plates or members 38 and 49 are 100 stamped from sheet metal, thus materially reducing the cost of manufacture of devices of this nature. The contact members and insulating members may be secured in position by means of eyelets which operation 105 further cheapens the manufacturing costs of the device.

Since the device, when used as a radio lamp, need be only six or eight inches in height, the same may by bending the joints 110 be doubled up to occupy a very small space for transporting the same by tourists. Furthermore, the joints will permit the support to be bent so that the lamp while being supported on the cabinet may be readily adjusted to properly illuminate the dial or dials thereon.

It is thought from the foregoing taken in connection with the accompanying drawings that the construction and operation of 120 my device will be apparent to those skilled in the art, and that various changes in size, shape, proportion and details of construction may be made without departing from the spirit and scope of the appended claims.

I claim as my invention:

1. In an electric lamp, a base, an electric switch in said base for opening and closing the circuit to said lamp, a rigid arm pivoted to said base, a hood pivoted to said arm, a 130

lamp socket in said hood, said socket being provided with two contact members, a conductor leading from said base through said arm to one of said contact members, a metallic connection between the other contact member and said arm whereby the same will constitute a return conductor from said socket to said switch.

2. In an electric lamp, a metallic base, an electric switch in said base, an arm, a friction hinge between said arm and base, a hood, a friction hinge between said arm and hood, a lamp socket, means for rigidly mounting said socket on said hood independently of said arm, and an electric bulb detachably mounted in said socket and carried thereby.

3. In an electric lamp, a hood curved in cross section, an insulating member secured to said hood, a bulb support comprising an angular plate provided at one end with an opening for receiving the base of an electric light bulb, said plate being provided with slots at opposite sides of said opening

and with depressions adjacent to said slots, means for securing said plate and member to said hood, a contact element secured to said member, a strip of insulating material extending about said element for insulating the same from said hood.

4. In an electric lamp, a metallic base having a recess therein, a switch within said base for opening and closing the circuit to said lamp, said switch comprising a plate of insulating material secured in said recess, spring-pressed contact members secured to said plate, conductor wires secured to said members, a rotating disk of insulating material having a pair of contact elements for engaging and disengaging said spring-pressed contact members, a conductor secured to one of said elements, means for grounding said other element on said base, and means extending through said base for operating said switch.

In testimony whereof I affix my signature.

CARL BRAMMING.
